UNITED STATES PATENT OFFICE.

JOHN L. C. HEINZ, OF CHICAGO, ILLINOIS.

HINGE MEANS FOR CASEMENT WINDOWS.

Application filed August 18, 1926. Serial No. 129,891.

My invention relates to hinge means for casement windows; and the main object of the invention is to provide hinge means of this kind which is arranged and provided 5 with means to gradually move the window upwardly and at the same time tilt it inwardly during the opening of the window, so that the upper end of the window is moved or tilted inwardly away from the 10 frame while the lower end is moved upwardly from behind the window stool during the window opening operation. A further object is to provide manual operating means on the hinges for positively moving the window into its closing position and likewise into its opening position; and a further object is to provide such manual means or lever means with means for positively retaining and locking the window in its closed position 15 behind the window stool and also for positively retaining or holding the window in its upper position or opening position.

Other objects and advantageous ends are attained with my invention, as will become 20 apparent from the following description taken in connection with the accompanying drawings, in which,

Fig. 1 is an elevational view of a casement window, with one window sash open 25 and the other closed, and having my improved hinge means or mechanism applied thereto;

Fig. 2 is a vertical cross sectional view on line 2—2 of Fig. 1, with the window closed;

Fig. 3 is an enlarged vertical sectional view on line 3—3 of Fig. 1;

Fig. 4 is a view similar to that shown in Fig. 3, but showing the window and hinge means in the opened position;

Fig. 5 is a vertical section on line 5—5 of Fig. 4;

Fig. 6 is a horizontal section on line 6—6 of Fig. 3;

Fig. 7 is an enlarged vertical sectional view on line 7—7 of Fig. 1;

Fig. 8 is a view similar to that shown in Fig. 7, but showing the window and hinge means in the opened position, and

Figs. 9 and 10 are sectional views taken 50 on lines 9—9 and 10—10 of Fig. 7.

In the drawings my improved hinge means or hinge mechanism is illustrated in con-

nection with a casement window including the window sashes 11 and 12, which are swingably mounted in the window frame 13 and have their upper ends 11' and 12' bevelled to fit closely under the bevelled edge 14' of the cap or head member 14 on the window; and these window sashes are provided with my improved hinge mechanism whereby the windows may be moved or tilted inwardly with the upper ends and at the same time the lower ends of the window are elevated or lifted up from behind the window stool 15 of the casement window.

My improved hinge mechanism or improved hinge means, as illustrated in these drawings, preferably comprises two main hinge means, 16 and 17, the means 16 being attached to the upper part of the window 55 and being arranged to permit inward tilting of the attached part of the window away from the window frame, and the hinge means 17 is attached to the lower part of the window and is arranged to permit upward sliding of the window from behind the window stool 15 and while the upper part of the window is moving inwardly from the frame 60 into the room.

The upper hinge means 16 preferably 65 comprises a hinge part 18 attached to the frame, with screws or any suitable fastening element, and a hinge part which is attached to the window sash and includes swingably connected elements 19 and 20, said elements 70 being preferably arranged in the form of a flap hinge with pintle barrels and a pintle 75 therein, to provide freely swinging and folding together of said elements during the operation of the window. The element 19 is 80 connected to the window sash, with screws 85 or any suitable fastening elements as indicated in the drawings. These two hinge parts are connected by a member or plate 21 85 which is pivotally connected by a pin 22 to a hinge part 18, and by a pin 23 to hinge element 20. A curved slot 24 is provided in part 18 for free movement therein of a pin 25 fastened on plate 21, and a curved slot 26 is provided in plate 21 for free movement 90 therein of a pin 27 fastened on element 20, said pins having enlarged heads, as shown 95 in the drawings, to prevent wobbling or tilting movement of the hinge parts and plate,

in planes transverse or at an angle relative to each other. The part 18 is preferably also provided with a base plate 28 set into the window frame and having suitable grooves or depressions therein to provide free movement of the heads of said pins and avoiding any cutting of a number of grooves in the frame.

The hinge means 17 preferably comprises a part 30 fastened on the window frame, and a part 31 fastened on the window sash, with suitable fastening elements. The part 30 has spaced pintle barrels 30', with a pintle 32, and the part 31 has a pintle barrel 31' 75
slidably longitudinally along the pintle, between the spaced barrels 30'. Said barrel 31' has an enlarged inner bore 31'', which is enlarged at one end or both ends, as best indicated in Fig. 9, so as to permit tilting or transverse inward movement of the window, especially the upper part thereof, away from the window frame, at the same time that the lower part of the window, and in fact the entire window, is being lifted vertically and upward from behind the window stool.

Manual means or lever means is provided for positively moving the window into its opened and also into its closed position, and furthermore, for retaining or holding the window and its attached hinged part either in such open or elevated position or in its closed or lowered position. This means comprises a lever 33 pivoted with a pin 34 on hinge part 30, between said part and a guide plate or covering band 35. The lever is provided with curved strips 36 and 37 forming a curved slot 38 therebetween in which travels the pintle barrel 31'. 80

It is apparent from the above disclosure that by moving the lever 33 into its downward position, as shown in Fig. 7, the curved outer finger or strip 36 forces the pintle barrel 31' with the hinge part 31 and the attached window positively into its closed position, with pintle barrel 31' moved to its lower limit of travel on pintle 32 and seated on the lower pintle barrel 30', and it also locks and retains the window in the closed position behind the window stool; and by moving said lever upwardly into its upper position, as shown in Fig. 8, the curved inner finger 37 moves pintle barrel 31' and hinge part 31 with the window upwardly and also holds and retains the same in such raised or upper position, with the barrel 31' at the upper limit of its travel on pintle 32, near the upper barrel 30'. It is also apparent that as the lever is swung upwardly and the entire window is being lifted, that at the same time the upper part of the window is tilted or swung away from the frame inwardly into the room, mainly due to the construction of the hinge means 16 at the upper part of the window; while the hinge means 17 at the lower part of the window

permits such tilting of the upper or main part of the window, due to the enlarged portions or ends of bore 31'' in pintle barrel 31'; and it is furthermore evident that both the hinge means 16 and the hinge means 17 co-operate in effectively tilting and moving the upper part of the window away from the frame, while the window is being lifted upwardly from behind the window stool, and also that the upper hinge means 16 shifts the upper part of the window with its attached hinge part bodily inwardly away from the frame and the hinge part 18.

What I claim as my invention and desire to secure by Letters Patent is:

1. Hinge means for a casement window, said hinge means comprising means fastened to the window near its upper part for tilting the upper part of the window inwardly from the frame and means apart from said first means to enable moving the lower part of the window upwardly from behind the window stool while the upper part is being tilted, and a lever with means for positively opening and closing the window and for holding it in its opened position and also in its closed position.

2. Hinge means comprising a foldable hinge part having leaves swingably connected, another hinge part, and a plate having pin means pivotally connected to one of said leaves and the other of said hinge parts to permit swinging movement of said parts with relation to each other.

3. Hinge means comprising a hinge part with elements swingably connected, another hinge part, and means pivotally connecting said two hinge parts and including slot and pin means with heads for preventing wobbling or relative tilting movement of one hinge part with respect to the other.

4. Hinge means comprising a part fastenable on the window frame and a part fastenable on the window, there being co-operating pintle barrels on said parts, and a lever with curved strips embracing said pintle barrel on the window part for positively moving said window and the attached hinge part vertically on the other hinge part and the frame and for locking said window in position.

5. Hinge means comprising a part with spaced pintle barrels and a pintle, a part with a pintle barrel slidably longitudinally on said pintle between said spaced barrels, and a lever with means for slidably engaging and positively moving said slidably pintle barrel and its hinge part in either direction on said pintle.

6. Hinge means comprising a part with spaced pintle barrels and a pintle, a part with a pintle barrel tiltable on said pintle and also slidably longitudinally along said pintle, and a lever with means for engaging both ends of said slidably barrel and for

positively moving it along said pintle, and for positively retaining it at either end of its travel on said pintle.

7. Hinge means comprising a leaf hinge part with spaced pintle barrels and a pintle therein, a part with a pintle barrel slideable longitudinally on said pintle between said spaced barrels and having a conical opening

enlarged at an end to permit tilting of said pintle barrel on said pintle, and means for moving and for retaining the slideable pintle barrel at either end of its travel.

In testimony whereof I have signed my name to this specification.

JOHN L. C. HEINZ.
